UNITED STATES PATENT OFFICE.

PATRICK McGIVERN AND WILLIAM E. FRYE, OF CRESTLINE, OHIO.

FEED-WATER HEATER.

SPECIFICATION forming part of Letters Patent No. 296,427, dated April 8, 1884.

Application filed October 27, 1883. (No model.)

To all whom it may concern:

Be it known that we, PATRICK McGIVERN and WILLIAM E. FRYE, both of Crestline, in the county of Crawford and State of Ohio, have 5 invented a new and Improved Feed-Water Heater, of which the following is a full, clear, and exact description.

Our invention consists of a detachably supported water table or heater located in the fire-box of a locomotive or other boiler, with feed-water and delivery pipe connections for heating the feed-water before entering the boiler proper, the said heater being supported by the pipe-connections and by connection with 15 the side sheets of the furnace, so as to be readily taken out for repairs; and the pipe-connections having outside joints back of the fire-box, under the boiler, where the joints can be connected or disconnected at will; and the 20 delivery-pipes are extended into the boiler and made to discharge at points where currents of water are set in motion by the inflowing jets, which act on the flues to protect them from 25 deposits of scale; and the heater is arranged with relation to the air-inlets of the door suitably for promoting such combustion of the gases rising from the fire-bed as will prevent the discharge of smoke, all as hereinafter fully described.

30 Reference is to be had to the accompanying drawings, forming part of this specification, in which similar letters of reference indicate corresponding parts in all the figures.

Figure 1 is a longitudinal sectional elevation of a locomotive-boiler provided with a 35 feed-water heater contrived in accordance with our invention. Fig. 2 is a transverse section taken on the line $x-x$ of Fig. 1, and Fig. 3 is a plan view of the water-table forming the feed-water heater.

40 A represents the water table or heater, which we arrange in the fire-box b , as shown in Fig. 1—that is, in an inclined position—rising from the back of the fire-box, below the tube-sheet, upward toward the front about as high as the 45 middle of the fire-door c , but terminating sufficiently short of it to allow suitable space for the gases to pass up in front of the fire-door, to receive sufficient fresh oxygen through the 50 air-passages thereof for complete combustion,

or nearly so, the said heater extending nearly from side to side of the fire-box b , and being detachably secured thereto by the brackets d , attached to the side sheets, and the clips e , attached to the heater, so as to have suitable 55 support, with freedom to expand and contract independently of the said side sheets.

At the back and lower edge of the heater it has three pipe-connections, $f g h$, which join with pipes extending through the fire-box b to 60 the exterior, where the middle pipe, f , connects with an outside section, i , of the feed-water pipe, and the other two pipes, $g h$, join with other outside pipes, $j j$, which enter the boiler, and terminate at k and l , respectively, for 65 delivering the feed-water at k from the heater a at the water-level, or thereabout, and above the tubes, and so that the water will flow along the tubes and return to the heater from the point l , which is much lower, and in the forward and colder part of the boiler, when the 70 pump or injector is not working, whereby a circulation will be established through the heater, and it will be kept full of water for its protection and for more effectually heating the 75 water than if the heater discharged into the boiler through one pipe only, in which case the water in the heater might be wholly converted into steam, so that the plates would be injured more by the fire. The current along 80 the tubes from k to l tends to keep the tubes clean. The feed-water pipe i terminates at the opening into the heater, and also the delivery-pipe j that terminates at l ; but the other delivery-pipe j extends up therein to the upper part, as shown at m , to receive the hottest water, which rises thereto and convey it therefrom into the boiler.

85 The feed-water pipe i connects with an inside section, n , by a goose-neck, o , and the section n extends, in this example, to the mud-drum p , near where the check-valve x is located in some forms of engines; but we do not limit ourselves to any particular location of the check-valve, nor to the arrangement of the 90 inside section, n , of the feed-pipe. The delivery-pipes $j j$ also connect with their inside sections by suitable goose-neck devices, Fig. 2, which may also be varied at will; but we consider it an essential part of our invention 95 100

that the feed and delivery pipes shall have detachable outside joints at *q*, in order that the pipes can be readily disconnected at any time for the removal of the heater. These 5 joints *q* may be constructed in any of the well-known ways for being disconnected, as by union-joints at *s*, or otherwise. We propose to construct the heater *a* by bending over a boiler-plate in the form represented in cross-10 section in Fig. 1, riveting the ends together, stay-bolting the two wide sides through from one to the other, and riveting flanged plates in the ends, with the flanges turned outward, so that the joints will not be much exposed to 15 the hot fire and will be very lasting.

The heater will have plugs in the ends, to be removed for access to clean the heater when required.

Having thus described our invention, what 20 we claim as new, and desire to secure by Letters Patent, is—

1. The water-table feed-water heater arranged in the fire-box, and removably secured to the sides thereof by brackets and clips, 25 and supported at its lower end by detachable feed and delivery pipe connections extending through the fire-box to the outside, whereby said pipes and feed-water heater may be disconnected for cleaning or repair without having to enter the fire-box.

2. The feed-water pipe connected to the wa-

ter-heater *a* by an outside section, *i*, connecting with an inside section, *n*, and connecting with the heater through the fire-box side and with a detachable joint, substantially as described. 35

3. The delivery-pipes *j, j*, connected to the water-heater *a* through the fire-box side, and by detachable joints, and having inside extensions discharging the water at or about the 40 water-level, and below it, and at opposite ends of the tube-section of the boiler, substantially as described.

4. In a feed-water heater for locomotive-boilers, located in the fire-box, two delivering-pipes extending therefrom into the tube-section of the boiler by outside connections through the fire-box and the bottom of the boiler, one of said pipes extending in the heater to the upper portion of the same and discharging at 45 or about the water-level at the rear ends of the tubes, and the other pipe opening into the lower part of the heater and discharging at a lower point in the boiler, near the front end of the tubes, to cause circulation of water in 50 the heater when the pump is not working, substantially as described.
